UNITED STATES PATENT OFFICE.

LLOYD H. SHAW, OF MOUNT PLEASANT, PENNSYLVANIA.

PUMPING SYSTEM.

1,250,368.

Specification of Letters Patent. Patented Dec. 18, 1917.

Application filed August 1, 1916. Serial No. 112,560.

To all whom it may concern:

Be it known that I, LLOYD H. SHAW, a citizen of the United States, residing at Mount Pleasant, in the county of Westmoreland and State of Pennsylvania, have invented certain new and useful Improvements in Pumping Systems, of which the following is a specification.

This invention relates to pumping systems, and more particularly to a system in which a plurality of pumping elements are connected to a closed supply circuit.

One of the main objects of the invention is to provide a pumping system of maximum capacity which requires a relatively small amount of power for its operation. A further object is to provide a system of simple construction and operation, the operative parts of which are so relatively disposed as to balance each other so as to reduce vibration. Further objects will appear from the detailed description.

In the drawings:

Figure 1 is a side view of the invention,

Fig. 2 is a top plan view, and

Fig. 3 is a section on line 3—3 of Fig. 2.

In carrying my invention into effect I provide a rectangular pipe frame 1. This frame is provided at the center of each side and of each end, respectively, with a T 2 adapted to be connected to a supply pipe leading from a sump or other suitable source of supply. Near each end of each side of the frame 1, T's 3 are secured in the frame. Each of these T's carries a valve casing 4 in which is mounted an upwardly opening inlet valve of usual construction. Each of the casings 4 communicates with a water cylinder at the longitudinal center thereof. A valve casing 6 is secured to the top of each cylinder 5, and each casing communicates with one end of a water head 7. Mounted in the casings 6 are upwardly opening discharge valves of standard construction. The waterheads 7 are connected by a cross pipe 8 which is provided at its longitudinal center with an air chamber 9.

A plunger rod 10 is mounted in each pair of water cylinders 5 and is provided, on each end, with a plunger head which fits snugly the interior of the cylinder, of usual construction, not shown. Each water cylinder is provided, at its inner end, with a packing flange 11 surrounding the plunger rod 10 so as to make a water tight closure. A flanged spacing ring 12 is secured between

the ends of the water cylinders 5 concentric therewith and acts to hold the cylinders in proper spaced relation and to protect the rod 10.

The inner end of rod 10 is connected to the inner end of a piston rod 13. This piston rod is connected to a cross head 14 slideable in a guide 15 secured between the inner water cylinder 5 and the steam cylinder 16.

The cylinder 16 is provided, on its inner side, with a valve casing 17 in which is mounted a slide valve of usual construction, which governs the admission and exhaust of steam into and from the cylinder, in the usual manner. The cylinder and the valve may be of any standard construction, being provided with suitable inlet and exhaust portways which communicate with the inlet pipe 18 and exhaust pipe 19, respectively.

Each valve has its ends connected by rods 20 to the inner ends of operating links 21. The outer end of each link is mounted on an eccentric 22 keyed on a shaft 23 which is rotatably mounted in standards 24.

A comparatively heavy fly wheel 25 is keyed at the center of shaft 23. At each end of the shaft is keyed a disk 26 provided on its outer face with an eccentric pin 27. A drive rod 28 has its outer end pivoted on the pin 27 and its inner end pivotally secured to the inner end of an arm 29 integral with the cross head 21 and projecting inwardly therefrom.

When steam is admitted to the cylinders 16, the pistons which are mounted therein so as to operate in the usual manner, and are connected to the piston rod 13, are reciprocated. This causes reciprocation of the plunger rod 10 and the cross heads 14. The cross heads act, through the rods 28 and

disks 26, to rotate the shaft 23 which causes rotation of the fly wheel 25. As the plunger rods 10 move outward, part of the water in the outer water cylinder 5 is forced upward through the valve casing 6 into the water head 7 and cross pipe 8. At the same time, an equal amount of water is drawn by suction into the inner cylinder 5. When the plunger rods move inward this operation is reversed, water being forced from the inner cylinders 5 into the head 7 and pipe 8, and an equal amount of water being drawn into the outer water cylinder. The water which is forced into the cross pipe 8 compresses the air in the chamber 9 which acts, in the usual manner, to force the water from the pipe

through the opening 30 of the water head 7.

which may be connected to suitable discharge pipes.

The eccentrics 22 are so relatively disposed on the shafts 23 that the diagonally opposite plunger rods will be similarly operated. This will be clear from Fig. 2 of the drawings. In this figure, the upper left hand and the lower right hand plunger rods are in extended or outward position, and the upper right hand and lower left hand rods are in withdrawn or inward position. The valves in the casings 17 are being moved toward the left hand end, and the right hand end, of the upper and lower casings, respectively. When the valves reach the ends of the casings, the exhaust 19 will be opened, and the inlet 18 will be opened in front of the pistons in the cylinders 16 so as to cause reverse movement of the same. This will cause the upper left hand and the lower right hand plunger rods to move inward, and the lower left hand and the upper right hand plunger rods to move outward, thus reversing the operation. By having the controlling mechanism so arranged that the diagonally opposite plunger rods move similarly, the vibration produced at one corner of the frame offsets to a great extent the vibration produced at the other corner, thus reducing the total vibration of the pumping system to a minimum.

The length of the stroke of the piston rods 13 is a little less than one half of the length of the water cylinder 5. By this arrangement, each cylinder is approximately either half emptied or half filled with each stroke. While the plunger 10 is acting to force the water out of one of the cylinders, it is also acting to suck an equal amount of water into the other cylinder. By this arrangement the plunger rod does practically twice the amount of work as is done by the plunger of a single action pump of ordinary construction. The fly wheels 25, due to their great momentum, are of material assistance in the operation of the plunger rods, acting to reciprocate the cross heads 14 by means of the drive rods 28. For this reason, very little more power is consumed in operating the plunger rods 10 for compression and suction purposes simultaneously than would be required for operating a similar plunger for a single action pump. By thus constructing and arranging the various elements of my pumping system I provide a system of maximum capacity for the power consumed which is of very simple construction and operation and in which the vibration is reduced to a minimum. Also, due to the continuity of the pipe frame 1, what little vibration is generated is evenly distributed throughout the whole pumping system, so as to cause a minimum of wear. By having an inclosed supply circuit provided with supply inlets at the center of each side and each end, re-

spectively, I insure that the water cylinders will at all times be properly supplied with a sufficient quantity of water for operating purposes. This pipe frame also acts as a supporting base and bracing medium for the various cylinders and valve casings, and co-acts with the same to provide a structure of great strength which occupies a minimum of space.

It will be obvious that certain changes can be made in the construction and arrangement of the different parts of my invention without departing from the field and scope of the same, and I intend to include all such changes as fall within the scope of the appended claims in this application, in which a preferred form only of the invention is disclosed.

What I claim, is:—

1. In a pumping system, an endless rectangular pipe supply frame, pairs of axially aligned pumping cylinders mounted within the frame adjacent each end, and equi-distant from the transverse center, thereof, said cylinders being secured directly to and communicating with said frame, water heads secured to the adjacent ends of each pair of cylinders and communicating therewith, cross-pipes secured to and communicating with the water heads of the pairs of cylinders at each end of the frame, operating cylinders mounted at the center of the frame in alignment longitudinally thereof with said pumping cylinders, plunger rods operable in said pairs of pumping cylinders, piston rods operable in said operating cylinders and operatively connected to the said plunger rods, and means for controlling the admission and exhaust of operating fluid to and from the operating cylinders so as to cause similar operation of the diagonally opposite plunger rods.

2. In a pumping system, an endless rectangular pipe supply frame, pairs of axially aligned pumping cylinders mounted within the frame adjacent each end, and equi-distant from the transverse center, thereof, said cylinders being secured directly to and communicating with said frame, water heads secured to the adjacent ends of each pair of cylinders and communicating therewith, cross-pipes secured to and communicating with the water heads of the pairs of cylinders at each end of the frame, transverse shafts rotatably mounted between the pairs of cylinders at each end of the frame, fly wheels secured thereon at the transverse center of the frame, disks secured on the ends of said shafts, operating cylinders mounted at the center of the frame in alignment longitudinally thereof with said pumping cylinders, plunger rods operable in said pairs of pumping cylinders, piston rods operable in said operating cylinders and operatively connected to the said plunger rods, oper-

ating rods having their inner ends connected to said piston rods so as to be reciprocated thereby and their outer ends eccentrically pivoted to said disks in reverse relation so as to cause rotation of said shaft when the piston rods are reciprocated, valve casings carried by said operating cylinders and adapted to contain valves for controlling the inlet and exhaust ports thereof, valve rods operable through the ends of each of said casings, and links pivoted thereto at

their inner ends and having their outer ends eccentrically connected to said transverse shafts, the eccentrics on said shafts being so related as to cause similar operation of the 15 diametrically opposite plunger rods.

In testimony whereof I affix my signature in presence of two witnesses.

LLOYD H. SHAW.
